United States Patent Office

Des. 185,348
Patented June 2, 1959

185,348

GROUND TRAINER FOR AIRCRAFT PERSONNEL

Elmer J. Clinton, Denville, N.J., assignor to Curtiss-Wright Corporation, a corporation of Delaware

Application September 20, 1957, Serial No. 47,796

Term of patent 14 years

(Cl. D13—1)

The figure is a perspective view taken from the top, front and one side of a ground trainer for aircraft personnel showing my new design.

The rear and side of the trainer not shown, are substantially plain.

I claim:

The ornamental design for a ground trainer for aircraft personnel, substantially as shown and described.
